GUN CHARGER

George A. Goepfrich, South Bend, Ind.

Application March 4, 1943, Serial No. 477,975

4 Claims. (Cl. 89—1)

1

This invention relates generally to automatic charging devices for automatic guns, and particularly to automatic charging devices for automatic guns of the type where the reloading operation is effected by the expansion of exploded gases in the barrel and behind the projectile.

Guns of this type will not reload in the event a dud cartridge has been inserted into the firing chamber, since there will be no exploding gases to move the breech block rearwardly to eject the fired cartridge and insert a fresh cartridge. Accordingly, these guns are ordinarily equipped with a charging cylinder for retracting the breech block thereof in order to eject the dud cartridge and insert a fresh cartridge in the feedway thereof. The retraction of the breech block ordinarily is accompanied by a small movement of a sear to hold the breech block in retracted position and allow the fresh cartridge to remain in the feedway ready to be moved forward into the firing chamber upon actuation of the sear. Since guns of this type are ordinarily located remotely from the operator, as for example when mounted in an aircraft, mechanical or electrical means must be provided to actuate the sear in order to effect automatic firing of the gun.

Since guns of this type may at times fire explosive projectiles, means must be provided to insure against the insertion of a fresh cartridge into the feedway of such a gun until after the dud cartridge has been ejected, since there would be likelihood that a premature explosion might take place in the breech block of the gun, with the consequent damage to the gun and to the aircraft in which it is mounted. As has been explained, since the guns are at times located remotely from the pilot, it becomes necessary to provide automatic means for recharging one or more of such guns automatically, at the same time insuring against the possibility of premature explosions. The invention accordingly makes use of novel means including a novel electrical circuit for effecting both manual charging of the guns to make them ready for automatic operation, and automatic charging of the guns whenever necessary once automatic operation has begun.

It is an object of this invention to provide an automatic charging system for gas operated automatic breech loading guns.

Another object is to provide a charging system for manual charging of the guns to make them ready for automatic operation, the manual charging being generally effected by the service crew before the aircraft is engaged in combat.

A further object is to provide an automatic

2

charging system for guns of the type mentioned above which will employ for operation fluid supplied by the fluid pressure system of an aircraft.

A still further object of the invention is to provide an automatic charging system which, after being put into operation, will not require the attention of the pilot.

Yet another object of the invention comprehends the provision of a novel control circuit for one or more of such guns, said control circuit being adapted to manual charging of the guns during servicing operations, and to automatic charging of the guns after servicing operations have been concluded.

15 A feature of the invention lies in the provision of automatic cut-out means for the charging system should one or more of the guns become jammed in such a fashion that neither manual nor automatic charging can be effected.

20 A still further object of the invention comprehends the inclusion of a novel charging mechanism for one or more of such guns, which will add but little to the weight of the guns, certain of the accessories of the gun being readily adaptable to the charging system, thereby decreasing the amount of weight necessary to be added to the aircraft, a very important consideration.

25 A yet further object is to provide a safety device so that charging can be safely accomplished during flight.

30 These and other objects of the invention will be apparent from a study of the description hereinafter, reference being had to the drawings which show a preferred embodiment of the invention. It is to be understood, however, that the invention is not limited by the embodiments shown, nor otherwise than by the terms of the claims subjoined.

35 In the drawings which illustrate the invention: Figure 1 is a fragmentary plan view of a gas operated automatic breech loading gun showing also in plan a charging cylinder mounted along one side thereof;

40 Figure 2 is a longitudinal enlarged horizontal section of the charging cylinder shown in Figure 1;

45 Figure 3 is a fragmentary elevation view of a pair of guns of the type shown in Figure 1, showing schematically a control circuit for the automatic charging system.

50 Referring now to Figure 1 there is shown a gun 10 having a breech block casing 12 which has mounted for reciprocation therein a breech block 14. Held by the breech block casing 12 is an ejector 16 which serves to throw downwardly

spent shells which are removed from the firing chamber by the retraction of the breech block 14 during normal gun operation.

Integral with the breech block casing 12 is a housing 18 containing a fluid motor for retracting the breech block 14 during manual operation or automatic operation of the charging system forming this invention. Within the housing 18 is a liner 19 having mounted for reciprocation therein a piston 20 which is normally urged to the right by a return spring 22 guided by a sleeve 24 supported by housing 18. Piston 20 is fitted with a skirt 26 which is adapted at times to contact a charging lug 28 formed as a part of the breech block 14 to retract, or move rearwardly, the breech block 14 in the event that reloading does not take place during normal operation of the gun. By rearward movement of the charging lug 28, contact is made with a switch actuator 30, which when moved rearwardly actuates a finger 32 to close a switch 34 mounted at the rear of gun 10. The switch actuator 30 is normally biased to the right by a spring 36, so that it clears the finger 32 to open switch 34 when the block 14 is in the forward position. A switch 38 is mounted at the forward end of the charging housing 18 and is adapted to close when the piston 20 moves rearwardly as a result of pressure supplied to the housing 18 at a port 40.

Referring now to Figure 3 of the drawings the guns 10 are shown with cylindrical ammunition canisters 42 which supply ammunition to the guns 10, and which are locked into place by a locking device 44.

For supplying fluid under pressure to the charging cylinder 18 at port 40 a fluid pressure system comprising a pump 45, accumulator 46 and a reservoir 48 is provided. For controlling the admission of fluid to each charging cylinder 18 a solenoid operated valve 50 is provided.

For supplying energy for the control circuit of the guns 10, and for supplying energy to firing solenoids 52 for operating sears 53 of each gun 10 a source of energy 54 is provided.

To get the system shown in Figure 3 ready for automatic charging the guns 10 must first be manually charged. Where the guns 10 are mounted in aircraft this is ordinarily accomplished on the ground. The system is so arranged that the armorer may manually charge each gun individually without affecting in any way the other guns of the system.

A combat switch 56 is provided which for manually controlling the charging of the gun may be closed on a contact 58, and for automatically or manually controlling the charging the gun may be closed on a pair of contacts 60 and 62. However, closing on contact 58 avoids the possibility of accidentally closing a trigger switch 64. With combat switch 56 closed on contact 58 current is passed through a lead 66 to a contact 68 of a manual controlled charging switch 70, which when closed passes current through a lead 72 to a thermal time limit switch 74 to the solenoid operated valve 50 which opens to admit fluid to the charging housing 18 to retract the breech block 14. It will be noted that when the manual controlled charging switch 70 is closed, the ground circuit for thermal time limit switch 74 is open at a switch arm 76. This will permit the breech block 14 to be held in retracted position for an indefinite period as long as manual controlled charging switch 70 is closed.

With the closing of the manual charging switch 70 the breech block 14 is moved to its rearward

position and the rear gun switch 34 is closed by the actuator 30 and switch finger 32. Switch 34 will continue to remain closed even if manual charging switch 70 is opened, since the breech block 14 will be held in retracted position by the sear of gun 10.

A trigger lockout 78 is put into its proper position for automatic charging by completing a circuit that energizes a relay 80 of the trigger lockout 78 through a lead 82 branching from lead 66 and through a lead 84 to ground through switch arm 78 at manual charging switch 70. Energization of the relay 80 attracts an armature 86 to the left closing upon point 88 at which position it remains even though relay 80 is deenergized, being attracted to the right only when a relay 90 is energized, under conditions later to be described.

Thus far has been described the manually controlled charging operation which makes the gun ready for automatic charging. With the breech block 14 in the retracted position a live cartridge supplied by the ammunition canister 42 is placed in position in the feedway of the gun 10.

Preliminary to automatic charging, which occurs only when defective ammunition has been supplied to the gun 10 and automatic reloading does not take place, the following operations take place in the circuits shown in Figure 3. With the combat switch 56 in the combat position, or closed on switch points 60 and 62, current is supplied through a lead 92 to the rear gun switch, whence it is passed through a lead 94 to energize a time delay relay 96, since the breech block 14 is in the rear position. It may be noted, also, that the same operation takes place when the combat switch 56 is in the manual charging position or closed on point 58. Energizing time delay relay 96 attracts its armature 98 to left, opening its contact point.

Under normal firing conditions, when the trigger switch 64 is closed the following circuits are made.

One circuit is through trigger switch 64, through a lead 100 and through a winding 104 of a compound relay 102 and thence to ground. Energizing winding 104 of relay 102 attracts an armature 106 thereof to the left closing its contact point; however, the circuit that is made by closing armature 106 on its contact point is still open at the armature 98 of time delay relay 96.

Closing of trigger switch 64 simultaneously energizes a firing relay 108 through a lead 110 which branches from lead 100, a lead 112, through armature 86, thence to ground through a lead 114 to an armature 116 of a pressure switch relay 118. Energizing the firing relay 108 moves its armature 120 to the left to pass current from the lead 66 to energize the firing solenoid 52, to actuate the sear of the gun 10. The breech block 14 of the gun will then be released and firing will start and continue automatically as long as the trigger switch 64 is closed. The cycle of reloading and firing the gun being shorter than the unloading period of the time delay relay 96, it continues in its energized state, being given a current impulse each time rear gun switch 34 is closed.

The circuit shown in Figure 3 remains unchanged as long as normal firing of the gun takes place, but if the gun misfires the following functions occur:

Since normal reciprocation of the breech block 14 will not occur after misfire, the breech block will remain in the forward position, thereby breaking the circuit periodically made at the rear

gun switch 34, thus deenergizing time delay relay 96, permitting its armature to fall to the right on its contact point. Current will then be passed from lead 66, through armature 106 of compound relay 102 (which is energized by winding 104 supplied with current by the lead 100), through lead 122, through armature 98 of time delay relay 96, through a lead 124 which connects to the lead 72 to the solenoid operated valve 50.

It will be noted that the heater element of thermal time limit switch 74 is now carrying current, ground being made through the switch arm 76 of the manual charging switch 78. If current to the solenoid operated valve is on for too long a time, which indicates that the breech block 14 for some reason cannot be retracted, thermal time limit switch 74 is opened.

Means are provided for insuring the completion of an automatic charging operation, once it has been initiated, regardless whether the trigger switch 64 has in the meantime been opened. A lead 126 branches from lead 72 near the thermal time limit switch 74 and is connected to a second winding 128 of the compound relay 102, insuring that the relay is energized as long as the circuit to the solenoid operated valve 50 is closed, regardless of the condition of trigger switch 64.

Simultaneously with the closing of the circuits discussed above which occur upon the failure of reciprocation of the breech block 14 is the closing of another circuit, made through a lead 130 branching from lead 72 near thermal time limit switch 74, to the relay 90, and thence to ground through a lead 132 and an armature 134 of the pressure switch relay 118. Closing of the circuit just described energizes relay 90 of the trigger lockout 78 to attract armature 86 to the right to deenergize relay 108 and break the circuit to the firing solenoid 52. It is now impossible to fire the guns 10 even though the trigger switch 64 is closed.

The functions described above occur instantaneously as the armature 98 of time delay relay 96 closes to the right. A fractional part of a second after these functions take place fluid will flow into charging cylinder 18 and will build up a pressure sufficient to close a pressure switch 136 operated by a pressure sensitive capsule 138. It may be noted that the equivalent is shown in Figure 2, the switch 38 closing as soon as the piston 20 has moved a sufficient distance to the left. Closing of switch 136 energizes the pressure switch relay 118, attracting armatures 116 and 134 to the left, thus opening the circuit to relay 90 and opening the circuit through armature 86 of the trigger lockout 78. It may be noted that the armature 86 does not close on contact 88 when relay 90 is deenergized.

For assisting in getting the circuit ready for normal operation of the gun 10, a case ejection switch 140 is closed when the spent cartridge case is ejected downwardly by the ejector 16 shown in Figure 1. Closing switch 140 energizes relay 80 of trigger lockout 78 to attract armature 86 to the left to close on contact point 88. This operation would normally energize firing relay 108 when trigger switch 64 is closed, but until the fluid is completely exhausted from the cylinder 18 to the reservoir 48 the pressure actuated switch 138 will remain closed to keep energized pressure switch relay 118 and keep armature 116 from its contact, thereby keeping the circuit to firing relay 108 open.

As the breech block 14 reaches its retracted position rear gun switch 34 will be closed, thereby

energizing time delay relay 96, thus opening the circuit to solenoid operated valve 50, which then will operate to connect cylinder 18 to the reservoir 48, permitting spring 22 to return piston 20 to its starting position. When the fluid is completely dissipated from cylinder 18, pressure switch 136 will open to deenergize pressure switch relay 118 to permit armatures 116 and 134 to close on their contact points.

The electrical system may be divided into two circuits. The first circuit comprises a battery 54, switch 56, wire 66, armature or switch 120, firing solenoid 52, wire 62, relays 80 and 118, pressure switch 136, ejection switch 140, switch 74, solenoid valve 50, relay 90, wire 132, armature 134, wire 126, and winding 128 of compound relay 102. The second circuit comprises the source or battery 54, switch 56, switch 64, wire 100, wire 110, relay 108, wire 112, armature 86, wire 114, armature 116, and winding 104 of compound relay 102.

As an alternate construction, the switch 38 of Figure 1 is adapted to open when piston 20 reaches its starting position, in the same manner deenergizing relay 118 as in Figure 3.

If the trigger switch 64 has been opened during the automatic charging operation just described, the firing solenoids will, of course, be deenergized, and the sear of gun 10 will hold breech block 14 in retracted position ready to be released when the sear is actuated by the closing of trigger switch 64.

If the trigger switch 64 has been held closed during the automatic charging operation the breech block 14 will snap forward with a fresh cartridge and will thereafter reciprocate during normal gun operation until for some reason an automatic charging cycle must once more be initiated.

While the circuit has been described as applied to one gun it is equally as well applied to two guns as shown in Figure 1, and as shown is, if desired, under the control of a single trigger switch.

The invention has been described in terms of a desirable embodiment thereof, but it is to be understood that the invention is not limited by the embodiment shown and described, nor otherwise than by the appended claims.

I claim:

1. In combination with a gun having a breech block reciprocable for charging the gun, a fluid pressure motor mounted on the gun and constructed and arranged to engage the breech block to move the same to a retracted position and then release it for countermovement, an electrical system comprising a first and a second circuit connected to a source of current, an electrically operated valve in the first circuit for controlling fluid to the motor and connected in the first circuit through an openable connection, a time delay relay in the first circuit constructed and arranged to respond to normal reciprocation of the breech block to open said openable connection and to respond to abnormal reciprocation of the breech block to permit closing of said openable connection, a switch in the first circuit normally open and constructed and arranged to be closed by the breech block when in a retracted position to connect the time delay relay in the first circuit, a normally open trigger switch in the second circuit, a firing mechanism in the first circuit and mounted on the gun for holding the breech block in a retracted position to be released at a predetermined time, said mechanism

being connected in the first circuit through a normally open connection, a relay in the second circuit constructed and arranged to respond to closing of the trigger switch for closing said normally open connection to said mechanism to cause release of the said breech block, said relay being connected in said second circuit through an openable connection, a relay in the first circuit constructed and arranged to open said openable connection to said relay in the second circuit to prevent connecting the firing mechanism in the first circuit before the fluid in the fluid motor has been completely exhausted to allow the breech block to return to its normal firing position, and a switch in the first circuit constructed and arranged to respond to fluid pressure in the motor for connecting the last mentioned relay in the first circuit to said circuit.

2. In combination with a gun having a breech block reciprocable for charging the gun, a fluid pressure motor mounted on the gun and constructed and arranged to engage the breech block to move the same to a retracted position and then release it for countermovement, an electrical system comprising a first and a second circuit connected to a source of current, an electrically operated valve in the first circuit for controlling fluid to the motor and connected in the first circuit through two openable connections in series, a time delay relay in the first circuit constructed and arranged to respond to normal reciprocation of the breech block to open one of said two openable connections and to respond to abnormal reciprocation of the breech block to permit closing of said one openable connection, a switch in the first circuit normally open and constructed and arranged to be closed by the breech block when in a retracted position to connect the time delay relay in the first circuit, a normally open trigger switch in the second circuit, a firing mechanism in the first circuit and mounted on the gun for holding the breech block in a retracted position to be released at a predetermined time, said mechanism being connected in the first circuit through a normally open connection, a relay in the second circuit constructed and arranged to respond to closing of the trigger switch for closing said normally open connection to said mechanism to cause release of the said breech block, said relay being connected in said second circuit through an openable connection, a relay in the first circuit constructed and arranged to open said openable connection to said relay in the second circuit to prevent connecting the firing mechanism to the first circuit before the fluid in the fluid motor has been completely exhausted to allow the breech block to return to its normal firing position, a switch in the first circuit constructed and arranged to respond to fluid pressure in the motor for connecting the last mentioned relay in the first circuit to said circuit, a compound relay in the first and second circuits and constructed and arranged to control the other of said two openable connections in the first circuit, said compound relay being connected in the second circuit through the trigger switch during normal gun operation, to close said other openable connection, and connected in the first circuit through said two openable connections during charging of the gun, so that a charging cycle once initiated will be completed irrespective of the position of the trigger switch, and a trigger lock-out mechanism in the first circuit and constructed and arranged therein to disconnect the relay in the second circuit therefrom during a charging cycle and to reconnect said relay in the second circuit when charging is completed, whereby said firing mechanism is rendered inoperative at times of charging.

3. In combination with a gun having a breech block reciprocable for charging the gun, a fluid pressure motor mounted on the gun and con-

structed and arranged to engage the breech block to move the same to a retracted position and then release it for countermovement, an electrical system comprising a first and a second circuit connected to a source of current, an electrically operated valve in the first circuit for controlling fluid to the motor and connected in the first circuit through two openable connections in series, a time delay relay in the first circuit constructed and arranged to respond to normal reciprocation of the breech block to open one of said two openable connections and to respond to abnormal reciprocation of the breech block to permit closing of said one openable connection, a switch in the first circuit normally open and constructed and arranged to be closed by the breech block when in a retracted position to connect the time delay relay in the first circuit, a normally open trigger switch in the second circuit, a firing mechanism in the first circuit and mounted on the gun for holding the breech block in a retracted position to be released at a predetermined time, said mechanism being connected in the first circuit through a normally open connection, a relay in the second circuit constructed and arranged to respond to closing the trigger switch for closing said normally open connection to said mechanism to cause release of the said breech block, said relay being connected in said second circuit through an openable connection, a relay in the first circuit constructed and arranged to open said openable connection to said relay in the second circuit to prevent connecting the firing mechanism to the first circuit before the fluid in the fluid motor has been completely exhausted to allow the breech block to return to its normal firing position, a switch in the first circuit constructed and arranged to respond to fluid pressure in the motor for connecting the last mentioned relay in the first circuit to said circuit, a compound relay in the first and second circuits and constructed and arranged to control the other of said two openable connections in the first circuit, said compound relay being connected in the second circuit through the trigger switch during normal gun operation, to close said other openable connection, and connected in the first circuit through said two openable connections during charging of the gun, so that a charging cycle once initiated will be completed irrespective of the position of the trigger switch, and a trigger lock-out mechanism in the first circuit and constructed and arranged therein to disconnect the relay in the second circuit therefrom during a charging cycle and to reconnect said relay in the second circuit when charging is completed, whereby said firing mechanism is rendered inoperative at times of charging.

4. In combination with a gun having a breech block reciprocable for charging the gun, a fluid pressure motor mounted on the gun and constructed and arranged to engage the breech block to move the same to a retracted position and then release it for countermovement, an electrical system comprising a first and a second circuit connected to a source of current, an electrically operated valve in the first circuit for controlling fluid to the motor and connected in the first circuit through two openable connections in series, a time delay relay in the first circuit constructed and arranged to respond to normal reciprocation of the breech block to open one of said two openable connections and to respond to abnormal reciprocation of the breech block to permit closing of said one openable connection,

a switch in the first circuit normally open and constructed and arranged to be closed by the breech block when in a retracted position to connect the time delay relay in the first circuit, a normally open trigger switch in the second circuit, a firing mechanism in the first circuit and mounted on the gun for holding the breech block in a retracted position to be released at a predetermined time, said mechanism being connected in the first circuit through a normally open connection, a relay in the second circuit constructed and arranged to respond to closing the trigger switch for closing said normally open connection to said mechanism to cause release of the said breech block, said relay being connected in said second circuit through an openable connection, a relay in the first circuit constructed and arranged to open said openable connection to said relay in the second circuit to prevent connecting the firing mechanism to the first circuit before the fluid in the fluid motor has been completely exhausted to allow the breech block to return to its normal firing position, a switch in the first circuit constructed and arranged to respond to fluid pressure in the motor for connecting the last mentioned relay in the first circuit to said circuit, a compound

relay in the first and second circuits and constructed and arranged to control the other of said two openable connections in the first circuit, said compound relay being connected in the second circuit through the trigger switch during normal gun operation, to close said other openable connection, and connected in the first circuit through said two openable connections during charging of the gun so that a charging cycle 5 once initiated will be completed irrespective of the position of the trigger switch, a trigger lock-out mechanism in the first circuit and constructed and arranged therein to disconnect the relay in the second circuit therefrom during a charging cycle and to reconnect said relay in the second circuit when charging is completed, to render said firing mechanism inoperative at times of charging, and means in the first circuit for manually controlling charging of the gun, said 10 means being constructed and arranged in the first circuit to connect the electrically operated valve in the first circuit to control fluid to the motor and to connect the trigger lock-out mechanism in the first circuit, whereby the gun and electrical system are put in order for normal gun operation and for automatic charging.
